ATTORNEY

UNITED STATES PATENT OFFICE

REGNAR TERRILD, OF BROOKLYN, NEW YORK

FUSE AND ITS INSULATOR

Application filed September 14, 1927. Serial No. 219,397.

This invention relates to cartridge-fuses, that is to fuses and their insulators, and the principles embodied in said device are equally applicable to renewable as well as 5 non-renewable cartridge-fuses.

While my device has a special application to fuses where the current does not exceed 60 amperes, the principles of same may nevertheless in a slightly modified form, be 10 applied to fuses, where a considerably greater electric current is involved, or the knife-blade shape is employed.

With regard to the aforesaid, the object 15 of my invention has thus been to provide a selfindicating cartridge-fuse of superior quality and construction, for the purpose of eliminating the several objectionable features invariably found in those used at present.

Some of these notable objectionable features are, that the fuses are difficult to remove with the fingers, that tools are required in some cases for their removal, and 25 the said tools too often cause short-circuits, that the spring clips on the cutouts are sometimes bent and broken off, that frequently the contact between the fuse ferrules and the spring clips is bad due to soft metal in 30 the clips, or bending caused by unskilled persons, and above anything else, that the ferrules of the 0-30 amps. fuse are so close together that a shock is likely to be received, when a fuse is being taken out or removed, in 35 case a person is standing on grounded conducting material.

The said defects are either remedied, or 40 the cause of same eliminated, in my present device, as will be hereinafter more fully shown and described.

As this device is very simple of construction, the manufacturing cost of same should be comparatively small.

With the above and other objects in view, 45 this invention consists of the novel features of construction, combination and arrangements of parts, hereinafter fully described, claimed and illustrated in the accompanying drawings forming parts of this specification, 50 and in which similar characters of reference

indicate corresponding parts in all views, and in which:

Figure 1 is a side-elevation of my device; Fig. 2 is a longitudinal, transverse sectional view of same; while Figs. 3 and 4 are detail views.

Referring more particularly to the drawings, 10 indicates a cartridge-fuse, comprising a preferably double tube, of which the inner one 12 is made of fibre and the outer one 11 of an asbestos composition; naturally the said materials are subject to variation without traversing the scope of this invention, furthermore the said features are not 60 the essence of same.

The said tube 10 has its bottom part at each side formed with an oblong recess, or slit 22, adapted to admit and securely hold two connecting members 13, the latter comprising each a substantially flat piece of 70 copper, or brass, bent upon itself to form two substantially annular, tubular sections at their respective ends, and having for their provision, the lower one 18 to establish the immediate connection with the current-conducting-medium, and the upper one, which is embedded in the said tube 10, to be connected to the fuse-link 15; it being understood that the said arrangement takes the 75 place of the brass-ferrules commonly found 80 in this kind of cartridge-fuses, and whose object it otherwise is to establish the external electrical connection outside of the latter.

The said members 13 are each upon their 85 upper tubular sections at the outer side thereof formed with a bent or enlarged partial flange 17, which in turn is provided with a tapped bore adapted to receive a screw-bolt 21 for the purpose of detachably 90 connecting a fuse-link 15 to the said members 13.

The aforesaid double-tube is at its ends provided with caps 14 made of a non-conducting material threaded upon the former, the 95 said caps being made with downwardly extending, flat projections 19, as one of several prominent features, aiming at the object of establishing a perfectly insulated fuse connection.

The said caps 14 are further, as shown, at their end-surfaces provided with a comparatively small central opening 16, which may be covered by any transparent material, and 5 the purpose of which is to permit inspection of the condition of the fuse-link, and the tube inside.

Formed integrally with the said double-tube, at the inner ends of the slits 22, are 10 two downwardly extending, flat projections 20, the latter being of a length almost equal to the members 13, and have for their object to effect on the inner side of the members 13 an insulating protection equal to that 15 provided by the projections 19 on the outer side thereof.

When the members 13 are mounted in the said double tube by way of the slits 22, as 20 shown in Figs. 1 and 2, the sides of, or walls produced by, the said slits are firmly 25 securing the said members 13 by a clamping action, accentuated by the tightening of the caps 14 unto said tube.

It is obvious that changes may be made in 25 the form, construction and arrangement of the several parts, as shown, within the scope of the appended claims, without departing from the spirit of the invention, and I do not therefore limit myself to the construction 30 and arrangement shown and described herein.

What I claim as new, and desire to secure by Letters Patent of the United States, is:

1. A device of the class described, comprising 35 a fuse-link and a cylindrical tube, the latter being provided with a plurality of downwardly extending insulating projections formed integrally therewith, end-caps mounted upon said tube and being likewise 40 provided with downward projections, members substantially of the shape as a figure 8, formed with an upper partial flange engaging the said fuse-link and adapted to close the electrical circuit by having their lower 45 portions mounted in suitable clips forming part of the external circuit, substantially as and for the purpose set forth.

2. A device of the class described, comprising 50 a cylindrical tube, a couple of inner downwardly extending projections formed integrally therewith; caps threaded upon said tube and being provided with central openings, the latter being closed by a transparent medium; electrically connecting members 55 formed substantially as an 8, and having their upper ends encased in the said tube, the latter being arranged with slits at its bottom for the purpose of securely holding the said connecting members by engaging 60 these at their narrow middle sections, each of the said connecting members having disposed upon the outer side of their upper encased portions downwardly extending flaps, each of the said flaps being formed 65 with a tapped bore in order to establish con-

nexion with a fuse-link-member, and a bolt securing the latter to the said flaps, substantially as and for the purpose set forth.

3. A two-layer tube of a substantially cylindrical shape, provided at its lower surface with a couple of slits, the latter being adapted to receive and securely hold two current-connecting members, each substantially shaped as an 8, the upper section of the said members being formed with a partial flange adapted to engage with a fuse-link; end-caps mounted upon said tube, the former being provided with downwardly extending projections, the latter in parallel with similar projections formed upon the said tube adjacent the slits, the said projections serving as insulating means in operating and manipulating the said cartridge-fuse; the said end-caps being provided with central openings in order to permit inspection of the condition of the interior of the said tube, substantially as and for the purpose set forth.

Signed at New York city in the county of New York and State of New York this 2nd day of September, A. D. 1927.
